DISPENSER FOR SCREW TOP CONTAINERS

William Keenan, Los Angeles, Calif.

Application October 19, 1954, Serial No. 463,115

2 Claims. (Cl. 222—363)

This invention relates to dispensers for fluent materials and more particularly to a dispenser for use with screw top containers of powdered, beverage making compositions.

An object of the invention is to provide a manually operated dispenser attachable to the screw threaded openings of containers for dispensing measured quantities of the contents and when not in use, serving as the container closure means.

Another object of the invention is to provide a dispensing apparatus of the above character which may be conveniently manufactured from a few readily molded plastic parts which are easily assembled into the completed dispenser.

A further object of the invention is to provide a dispenser of the above character in which the dispensing apparatus is designed for attachment to standard screw threaded container closure caps.

Still another object of the invention is to provide a dispensing device of the above character which is economical to manufacture and is reliable in use.

With the foregoing objects in view, together with such additional objects and advantages as may subsequently appear, the invention resides in the parts, and in the construction, combination and arrangement of parts disclosed, by way of example, in the following specification of a satisfactory embodiment of the invention; reference being had to the accompanying drawings which form a part of said specification and in which drawings:

Fig. 1 is a side elevation of a container having a dispenser embodying the present invention applied thereto; the container being shown in upright or storage position,

Fig. 2 is an enlarged, fragmentary, side elevation of the container inverted with the dispenser attached thereto in position for dispensing the container contents,

Fig. 3 is an elevational view of the left hand end of Fig. 2,

Fig. 4 is a medial sectional view taken on the line 4—4 of Fig. 3, showing the dispenser valve element in the position to receive contents from the container,

Fig. 5 is a medial sectional view taken on the line 5—5 of Fig. 2 showing the valve element turned to dispensing position,

Fig. 6 is a reduced scale, top plan view of Fig. 5; portions being broken away to show details of construction, and

Fig. 7 is an exploded, side elevational view of the component parts of the illustrated embodiment of the invention.

Broadly, the illustrated embodiment of the invention comprises a stationary frame assembly generally designated by the numeral 1 and a oscillatable valve assembly mounted in the frame assembly and designated by the numeral 2. The frame assembly includes a frame member 3 having a funnel-like opening 4 terminating in a flange surface 5 including an annular rib 6 which projects through an opening 7 in a screw threaded cap 8 adapted to be substituted for the cap normally closing

the mouth of the container to which the dispenser is to be applied. At one point in its periphery, the rib 6 is interrupted by a notch 9 into which a radially inwardly projecting tongue 10 in the periphery of the cap opening 7 extends to prevent turning of the frame member in the cap. A ring 11 having a shoulder 12 engages the inner surface of the rib 6 and lies on the inner surface of the cap; the frame member and ring preferably being formed from plastic moldings and the ring 11 being cemented to the inner face of the rib 6 to complete the assembly of the cap and frame member. The inner surface of the ring is shaped to form the upper portion of the funnel portion 4 when the container and dispenser are inverted for a dispensing operation as shown in Figs. 2 and 4.

The dispensing valve assembly 2 comprises a hollow cylindrical valve element 13 having an opening 14 in the side thereof for reception and discharge of dispensed material and an open end closed by an end plate 15 having a raised portion 16 closely fitting within the inner periphery of the side wall 17 of the valve element and including a radially extending portion 18 of the same radial dimension as the outer face of said side wall extending across the opening 14 and completing the bearing surface of that end of the valve element in engaging the bearing portion 19 of the frame member 3. The opposite end wall 20 of the valve member 13 is formed integrally with the side wall and includes an outwardly projecting stub shaft 21 disposed in axial alignment with the axial line of the valve member body; said stub shaft extending through a bearing portion 22 on the frame member 3 and externally thereof engaging the hollow stem 23 of a hand knob 24 (see Fig. 4). The valve member assembly parts are all formed of plastic wherefore they can be readily assembled in permanent form by cementing them together; the above described separate parts being readily molded by injection molding. The end plate 15 includes an annular flange portion 25 which engages the outer face of the bearing portion 19 of the frame member and the end of the hand knob stem 23 similarly engages the outer face of the bearing portion 22 and cooperates with the flange 25 to secure the valve element against endwise movement. Additionally, the flange 25 carries substantially diametrically oppositely radially extending stop lugs 26 and 27 adapted to engage a stop member 28 projecting laterally from the side of the bearing member portion 19 (see Fig. 3) and serving, respectively, to position the opening 14 of the valve member either in position to receive material from the container (see Fig. 4) or to discharge received material (see Fig. 5). In this connection, it is to be noted that the projection 18 of the end plate 15 by its engagement with the side wall 17 of the valve member is correctly positioned so that the lugs 26 and 27 are properly positioned with respect to the opening 14 of the valve opening, and that said projection additionally serves to complete the required cylindrical bearing surface of the valve member for engagement with the interior of the bearing portion 19 of the frame member 3.

Preferably, the end plate 15 is first cemented into the end of the valve member and the completed valve member is then inserted into the frame member and secured therein by assembly of the hand knob thereto.

The assembled dispensers are then ready for assembly into caps of the desired size for use with specific containers; such containers being made with about four standard sizes of threaded openings. The assembled dispenser is then inserted into the selected size of screw cap and secured therein by cementing the ring 11 thereon.

In use, the dispenser is attached to the desired container in place of the regular cap therefor and the con-

tainer is inverted. Rotation of the hand knob to the position in which the lug 26 engages the stop member 28 positions the opening 14 of the valve member in alignment with the funnel opening 4 of the frame member with resultant flow of the container contents into the valve member. Rotation of the valve member to the point at which the lug 27 engages the stop member will bring the opening 14 to the position shown in Fig. 6 with resultant discharge of the contents of the valve member; the side wall 17 serving at the same time to cut off further flow of the contents of the container. Generally, beverage forming fluent materials such as soluble coffees, powdered milk and like products are directed to be used in quantities of one or more teaspoons and for general use, the above described dispenser would be dimensioned to hold one teaspoonful, but for some uses the valve member might be differently dimensioned. When not in use, the device is preferably moved to the position shown in Fig. 5 since the joint between the valve member and the contacting surfaces of the frame member including the bearing surface of the bearing portion 19, the engagement between the outer surface of the end wall 20 of the valve member with the inner face of the bearing portion 22 of the frame member, and the bearing of the outer surface of the side wall 17 of the valve member with the similarly curved portions 29 of the frame member extending between the upper portions of the bearing portions 19 and 22 is sufficiently close to form an adequate seal.

Thus there has been created a dispenser for use with screw top containers which is simple in construction and readily manufactured from injection molded parts and which can be readily substituted for the screw top caps used for such containers. It is appreciated that in the light of the foregoing disclosure changes and modifications may suggest themselves to others skilled in the art to which the invention appertains. Therefore, the invention is not to be deemed to be limited to the exact form thereof above disclosed by way of example, and it will be understood that the invention includes all such modifications and changes in the parts, and in the construction, combination and arrangement of parts as shall come within the purview of the appended claims.

I claim:

1. In a means for dispensing measured amounts of fluent materials from a screw top container and attachable to the container in place of the screw cap normally employed to close the container, the combination of an internally threaded cap engageable with the threads on the container and having an opening in the end thereof, and a dispensing means attached to said opening in said

5 cap; said dispensing means comprising a frame member having a funnel portion affording communication from said container to a dispensing valve means, a first bearing member projecting from one side of said frame member and having a circular opening extending therethrough, a second bearing member projecting from the opposite side of said frame member and having a circular opening extending therethrough disposed in axial alignment with said opening in said first bearing member, 10 a valve member journaled in said bearing members for oscillation between a position receiving material from the container and another position discharging received material; said valve member comprising a hollow, cylindrical body portion having an opening in the side thereof and an integrally formed end wall at one end thereof; said end wall including a stub shaft disposed axially with respect to said body portion and journaled in said opening in said second bearing member, an end plate closing the opposite of said body portion and including a portion 15 fitting within the inner periphery of said body portion and another portion completing the circular outer periphery of said body portion with resultant formation of a circular bearing surface journaled in said opening in said first bearing member, a fixed abutment on said first frame member, a pair of spaced abutments on said end plate engageable with said fixed abutment with resultant determination of said material receiving and discharging positions, and a hand knob connected to said stub shaft exteriorly of said second bearing member and cooperating with said end wall by engagement with the opposite side surfaces of said second bearing member to secure said valve member against endwise movement.

2. A dispensing means as claimed in claim 1 in which the end of said funnel portion remote from said valve member is attached to the container cap and includes an annular wall portion projecting through the container cap opening; said wall being interrupted by a transverse slot and said opening in the container cap including a tongue extending into said opening with resultant prevention of relative rotation between the cap and the dispensing means, and a ring secured to the interior surface of said wall and thence overlying the inner surface of said cap effective to secure the dispensing means to the cap.
